UNITED STATES PATENT OFFICE.

FRED E. HULT, OF JAMESTOWN, NEW YORK.

RAIL JOINT AND CHAIR.

1,099,302.

Specification of Letters Patent. Patented June 9, 1914.

Application filed May 28, 1913. Serial No. 770,454.

To all whom it may concern:

Be it known that I, FRED E. HULT, a citizen of the United States, residing at Jamestown, in the county of Chautauqua, 5 State of New York, have invented certain new and useful Improvements in Rail Joints and Chairs; and I do hereby declare the following to be a full, clear, and exact description of the invention, such as will 10 enable others skilled in the art to which it appertains to make and use the same.

This invention relates to rail joints, and it more particularly relates to an improved rail end fastener.

15 An object of the invention is to provide a rail joint of this character whereby the use of bolts and nuts is entirely dispensed with.

Another object of the invention is to provide a rail joint of this character which is more easily applied than other well-known devices intended for this purpose.

Another object is to provide a rail end fastener which also constitutes a rail chair.

25 Another object of the invention is to provide a device of this character which may be made entirely from sheet metal, by the ordinary and comparatively inexpensive methods of shearing, punching and bending sheet metal.

Another object is to provide a device of this character which is comparatively inexpensive and thoroughly efficient.

Other objects and advantages may be re- 30 cited hereinafter and in the claims.

In the accompanying drawings, which supplement this specification: Figure 1 is a side elevation view of two contiguous rail ends with my improved rail end fastener 40 and chair applied thereto. Fig. 2 is a view similar to Fig. 1, as seen from the opposite side. Fig. 3 is a bottom plan view. Fig. 4 is a vertical sectional view taken on the line 4-4 of Fig. 1. Fig. 5 is a perspective 45 view of one of the fastener members, and Fig. 6 is a perspective view of one of the base plates.

Referring to these drawings, in which similar reference characters correspond with 50 similar parts, throughout the several views, the rail ends 10 are each formed with a series of longitudinal slots or apertures 11, the opposite ends of each rail being of similar construction. The apertures 11 are ar- 55 ranged on a common plane, and may be

located at any desired elevation within the rail web.

The rail end fastener comprises two fastener members 12 and 13 respectively and two base plates 14, the latter being preferably of similar and interchangeable construction.

The fastener member 12 comprises a base flange 15, an inclined side plate 16, apertured or slotted tongues or horizontal extensions 17, and vertical extensions or tongues 18 and 19.

The member 13 comprises a base flange 20, and an inclined plate 21, this plate 21 being provided with arms or upward extensions 70 22, each having its free end folded upon itself at 23 and terminating in a vertical and depending end 24.

Each base plate 14 comprises a horizontal base portion 25 having two opposite edges 75 curved upward and inward to form inclined lateral flanges 26, each said flange being apertured at 27 for the reception of railroad spikes. Each plate 14 is also provided with laterally extending tongues 28, one at each 80 of its corners. The flanges 26 of each base plate are slightly convergent, so that the space between said flanges is greater at one end than at the other.

In assembling the several members of the 85 rail end fastener, with the contiguous rail ends, the base plates or shoes 14 are first placed on the base flanges of the respective rails, with the flanges 26 diverging toward the respective rail ends, the space between 90 said base plates being greater than the length of the fastener members 12 and 13, so that these members may be passed between said base plates, with the base flanges 15 and 20 fitted snugly under the base 95 flanges of the rails 10, while the tongues 17 extend through the apertures or slots 11, and the angularly bent end portions 23 extend through the respective apertures 17'. The base plates are next slid along the base 100 flanges of the rails 10 until the apexes 12' and 13' are compressed by the respective flanges 26. It will be seen that as the members 14 are forced upon the apexes of the members 12 and 13, the convergent flanges 26 exert a wedging action for drawing these members tightly against the base flange of the rail for clamping the latter tightly and preventing relative lateral movement of the rail ends. The material from which the ele- 110

ments 22 are formed is preferably somewhat springy so that when the angular end portions 23 are forced into the respective slots 17', the depending elements 24 press against 5 the rail web, while the opposite portions of the elements 22 press against the respective tongues 17, so as to draw the flanges or extensions 18 and 19 snugly against the side of the rail web opposite to the extensions 10 24. The several members of the rail end fastener now being in assembled position, spikes of ordinary construction are driven into the ties contiguous to the tongues 28, or within the apertures 27 or both, to prevent 15 relative longitudinal movement of the base plates and members 12 and 13, said members being provided with notches 12^a into which the spikes extend.

It will be seen that I have provided a rail 20 joint of this character, which is fully capable of attaining the foregoing objects, in a thoroughly practical and efficient manner.

I do not limit my invention to the exact details of construction, combination and 25 arrangement of parts, as herewith illustrated and described, but my invention may only be limited by a reasonable interpretation of the claims.

I claim:—

30 1. A combined rail end fastener and chair consisting of two base plates each having opposite upwardly and inwardly inclined flanges, a fastener member comprising a base plate and an upwardly and inwardly inclined plate having apertured horizontal extensions adapted to be extended through an apertured rail web, a second fastener member comprising a base plate and an upwardly and inwardly inclined plate, the last 35 40 45 said plate having arms with their free end portions bent downward to form depending vertical elements which are adapted to be seated against the rail web while extending through said apertured tongues and coacting therewith and with the adjacent portion of said arms and with the said base plates, for tightly clamping the base flange and web of a railroad rail.

2. In combination with two contiguous 50 longitudinally slotted rail ends, a sheet metal member formed with a base flange and

an upwardly and inwardly inclined plate adapted to fit snugly and extend over the base flange of the rail, said upwardly and inwardly inclined plate being provided with 55 slotted tongues which extend through the respective slots of the rail web, a second sheet metal member formed with a base flange and an upwardly inclined plate fitted under and extending over said base flange 60 and having arms extending through the respective slots of said tongue, and a pair of base plates each provided with upwardly and inwardly extending flanges engaging with the first said and second said upwardly and inwardly inclined plates, for 65 binding the latter snugly against the rail flanges.

3. In combination with two adjacent rail ends having apertured webs and having base 70 flanges, of a fastener member comprising a sheet of metal formed with a base flange and with apertured tongues, a second plate of sheet metal formed with a base flange and with elements extending through the 75 apertures of the tongues, a base plate having means thereon for engaging the first said plate and the second said plate and binding the base flanges thereof tightly against the base flange of the rail, and means for securing 80 the base plates in fixed relation to a railroad tie and to the first and second said plates.

4. The combination with two adjacent rail ends each having a web and a base flange, 85 of two plates each formed with a base flange engaging the edge face of the base flange of the rail and with an upwardly and inwardly inclined element adapted for engagement with the rail web, and two base plates 90 each of which is formed with a pair of upwardly and inwardly inclined flanges which are convergent toward the web of the rail in a horizontal plane and adapted to be forced upon said plates for binding them tightly 95 against the base flanges of the rails.

In testimony whereof, I affix my signature, in the presence of two witnesses.

FRED E. HULT.
